Patented Oct. 9, 1928.

UNITED STATES PATENT OFFICE.

PLATO G. EMERY, OF CHICAGO, ILLINOIS.

CURTAIN FIXTURE.

Application filed May 15, 1924. Serial No. 713,405.

In one of its aspects my invention may be said to have for its object to produce a locking pawl device for the shoe of the shade stick, operating on the same principle as that described and claimed in my prior application, Serial No. 543,319, filed March 13, 1922; the device being somewhat simpler in construction than the specific device illustrated in the aforesaid application.

Viewed in another of its aspects my invention may be said to have for its object to overcome the rattling noises that are usually present in shade sticks when the cars by which they are carried are running.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a longitudinal section through one-half of a shade stick embodying the present invention; Fig. 2 is a section, on a larger scale than Fig. 1 through the middle portion of a modified construction of shade stick; Fig. 3 is a section taken approximately on line 3—3 of Fig. 2; Fig. 4 is an elevation of the middle portion of the capsule-like part contained within the shade stick in Fig. 2; and Fig. 5 is a plan of the blank, in its flattened condition, from which the said capsule-like part is formed.

Referring to Fig. 1 of the drawing, 1 represents a tubular shade stick of any usual or suitable construction. At the center of the same are finger pieces of which one only, indicated at 2 is shown. Each finger piece has a part extending inwardly through an elongated slot 3 in the stick and provided at its inner end with a screw threaded hub 4. At each end of the stick is a shoe 5 which may conveniently be in the form of a channel the trough of which is directed outwardly. Each shoe is fixed on the end of a rod 6 extending through the shade stick to the corresponding finger piece, being screwed into the hub of such finger piece. With each rod is associated a spring 7 tending to move the rod in a direction to carry the shoe outwardly from the end of the stick.

The shoes are provided with suitable anti-friction devices, such as rollers, 8 at the ends thereof. Between each roller and the middle portion of the shoe is placed an L-shaped pawl

9 pivotally supported at the angle thereof as indicated at 10. I prefer to employ two of these pawls although it will, of course, be understood that the principle of operation will be the same if there be only one pawl. The pawls are so proportioned that when the shoe is held vertically in the position it occupies in a window, one arm of each pawl will extend horizontally out through the mouth of the channel, while the other arm will butt against the bottom of the channel; the outermost ends of the pawls extending slightly beyond a line tangent to the outer sides of the two anti-friction rollers. The result is that when the shade stick is in use, the shade may be drawn down with the anti-friction rollers in engagement with the windowframe, while the pawls simply swing in a clockwise direction as viewed in Fig. 1 and trail idly along the frame. When the finger pieces are released at the end of a downward pull on the shade, the spring in the shade roller tends to roll up the shade, thereby raising the shade stick. At the instant that the shade stick starts to rise, the pawls become active, gripping the wood of the windowframe and beginning to turn in the counter clockwise direction. As the pawls grip the frame they push the shoe away from the latter so that the anti-friction rollers are held out of engagement with the frame. In other words, the shade may be pulled down freely but will be locked positively in any position into which it may be brought, until the pawls are disengaged from the windowframe by pressing the finger pieces toward each other in the usual way. When the shoe is turned end for end, those arms of the pawls that are occupying horizontal positions as viewed in Fig. 1 become the vertical arms, while the other two arms assume horizontal positions; the pawls swinging through an angle of 90 deg., by gravity, whenever the shoe is turned end for end.

Shade sticks usually rattle more or less when the cars in which they are mounted are running; and, where there are many shades, the combined rattling noises are disagreeable and annoying. Substantially, the entire noise is produced by the vibration of the inner ends of the rods carrying the shoes. I have found that by eliminating vibration at this point to the extent of avoiding the striking of metal against metal, the objection to which I have just referred is overcome. For the purpose of reducing vibration and pre-

venting the striking of metal against metal, I have placed within the shade stick, near each finger piece, a suitable sound-deadening cushion 11 that serves as a bearing for the rod. The member 11 may consist of a simple block or plug of felt or rubber held in place between two followers 12, 12 fixed within the stick on opposite sides of such member; the member 11 fitting snugly upon the rod 6, while the members 12 are provided with comparatively large openings 13 through which the rod passes. The cushion prevents vibration of the inner end of the rod to such an extent that the rod will not come in contact with any part of the followers.

If desired, the anti-friction wheels may be made of fibre or other noise-deadening material, thus reducing the slight amount of noise that can be caused by metal wheels.

In Figs. 2-5 I have shown a slightly modified cushion arrangement in which the cushions are located in a capsule that is inserted in the shade stick as a complete unit. The capsule may be made out of a single piece of sheet metal shown in its flattened condition in Fig. 5. The body portion 14 of the blank is substantially a rectangle having similar elongated notches 15 in two opposed sides. At the ends are two disk-like ears 16, perforated at the center as indicated at 17. Two rows of ears, 18 and 19, extending transversely across the blank a short distance from the two ends, are struck up out of the material of the blank. In the middle of the blank, on opposite sides of the longitudinal center, are a plurality of holes 20. The blank is bent or rolled to form a cylinder, a block 21 having lateral projections 22 adapted to fit into the holes 20 in the blank, being preferably placed on the blank before the latter has been completely formed into a cylinder. The block 21 may be provided with still another projection 23 that will fit into the slot produced by the bringing into registration with each other of the notches 15. After the blank has been formed into a cylinder with the ears or lugs 18 and 19 directed inwardly, the cushions 24 are inserted in the ends of the device and, when the disk-like ears 16 are bent laterally to form the ends of the cylinder, the cushions will be clamped in place between these ears and the lugs 18 and 19. This completed capsule is then inserted in the shade stick, and the rods are passed through the cushions and provided with the usual finger pieces. The block 21 serves both as a stop to limit the inward movement of the rods, and also as a point of attachment for an escutch-

eon plate which is in place by screw 26 passing into the block 21.

The hole 17 in the ends of the capsule are sufficiently large to prevent the rods from coming in contact with the metal of the capsule and therefore even though the rods should tend to chatter, there would be no metal to metal contact and consequently no noise.

While I have illustrated and described with particularity only a single preferred form of my invention, together with a slight modification, I do not desire to be limited to the exact structural details thus illustrated and described; but intend to cover all forms and arrangements which come within the terms employed in the definitions of my invention constituting the appended claims.

I claim:

1. The combination with a shade stick, of a shoe at an end thereof provided with anti-friction devices adapted to ride along a stationary frame member, and an L-shaped pawl pivoted at the angle thereof to the shoe so as to be capable of swinging by gravity between a position in which one of its arms is parallel with the rod and projects out past the line of contact of the said anti-friction devices and a position in which the other arm lies parallel to the rod and projects out past said line.

2. The combination with a shade stick, of a shoe at one end thereof provided with anti-friction devices at the ends adapted to ride along a stationary frame member, two L-shaped pawls spaced apart along the shoe and pivoted to the latter; the construction of the pawls and the pivotal connections being such that when the shoe is held vertical one arm of each pawl extends outwardly past the line of contact of the anti-friction devices and upon turning the shoe end for end, the pawls tend to swing by gravity into position in which the other arms thereof extend out past said line.

3. An article of manufacture comprising a short block having peripheral lugs, a sheet metal member bent into the form of a cylinder around said block and having holes at about the middle to receive said lugs, perforated plugs of sound-deadening material in the ends of said cylinder, and ears formed out of the metal of said member and engaged with the ends of each plug to hold it in place.

In testimony whereof, I sign this specification.

PLATO G. EMERY.
